UNITED STATES PATENT OFFICE.

ANDREW PETERSON, OF METALINE, WASHINGTON.

SAW-CLAMP.

1,028,775.

Specification of Letters Patent. Patented June 4, 1912.

Application filed December 8, 1910. Serial No. 596,295.

To all whom it may concern:

Be it known that I, ANDREW PETERSON, a citizen of the United States, residing at Metaline, in the county of Stevens, State of Washington, have invented certain new and useful Improvements in Saw-Clamps; and I do hereby declare the following to be a full, clear, and exact description of the invention, such as will enable others skilled in the art to which it appertains to make and use the same.

My invention relates to improvements in saw clamps and my object is to improve the construction and increase the efficiency and utility of devices of this character.

A further object of the invention is to provide a form of saw clamp which will be readily attachable to tables, benches or the like, and it will also be understood that a primary object which governs to some extent every other consideration is to reduce the cost of the device to the lowest limit consistent with efficiency and durability.

With the above and other objects in view the invention consists primarily in a slotted U-shaped frame, comprising an upper horizontal stationary jaw, a horizontal slidable jaw to coat therewith, means for actuating said sliding jaw and means for securing the device as a whole to a suitable support.

The invention further consists in a certain construction and arrangement of parts and details as is hereinafter more fully described, specifically pointed out in the appended claims and illustrated in the accompanying drawings which show a preferred embodiment of the invention.

In these drawings which are attached and form a part of this application, Figure 1 is a plan view of the device, Fig. 2 is a front elevation thereof, Fig. 3 is an end elevation, and Fig. 4 is a detail perspective view of the actuating cam lever. Fig. 5 is a fragmentary elevation showing how one of the clamp members is secured to the main bar of the frame.

Referring more specifically to these views in which similar reference numerals designate corresponding parts throughout, 1 indicates in general the frame of the device which as shown comprises a main longitudinal bar 2 to which are pivotally secured the depending end bars 3 and 4. It will be seen that these bars are hinged to the horizontal frame bar at the points 6 and 7. Each of the end bars is return-bent to form

the slot 5 and the end of the return-bent section is provided with a hinge connection 8 co-axial with the hinges 6 and 7 and supported by these hinges 8 is the outer or stationary jaw 9.

Adjacent the ends of the frame member 2 are a pair of vertical studs 10 and intermediate the length of the bar is a central stud 11. Slidably mounted, for transverse movement by means of slots 12 coacting with these studs is the slidable jaw or clamp, here designated as 14. In order to force this jaw outwardly a cam lever 15 is pivoted at 16 to the stud 11 and it will be seen that by causing this lever to rotate right-handedly the cam face 17 will engage the member 14 and a saw positioned in the slot, between the members 9 and 14 will be securely gripped. In order to afford a better grip and to prevent chattering of the saw blade while it is being operated upon a cord or strip 19 of resilient substance is stretched across the face of the jaw 14, and as a further preventive against chattering it may be desirable to form the contacting or bearing faces of the jaws as curves of comparatively long radius.

In order to secure the clamp thus described to a work-bench, table or the like the depending members 3 and 4 are provided with laterally extending arms 20, through which are threaded clamp screws 21, which as shown are of the conventional type and provided with thumb grips 23. Vertically above the clamp screws the top frame member 2 has extended portions 24. Referring to the end elevation of Fig. 3 it will be seen that the edge of a table may be gripped between the clamp screw and the top member 24 and the whole device thus firmly secured.

My improved saw clamp is adapted for use with straight edge saws of various types, can be extended into the straight line form for packing the same in tool boxes or for shipment, and is believed to fulfil satisfactorily the requirements of simplicity and reasonable cost of manufacture in that it consists largely of standard elements, contains few moving parts and these so arranged that the danger of derangement is reduced to a minimum.

What is claimed is:

1. In a device of the class described, a U-shaped frame having spaced apart transverse members and slotted vertical members, hinged connections between said transverse

members and said vertical members, a movable jaw carried by said frame, means for actuating said jaw, and means for securing said frame to a suitable support.

5. 2. In a device of the class described, a horizontal frame member, a pair of depending **U**-shaped members hingedly secured to the ends of said frame member, a stationary jaw carried on pivots secured in the return-bent ends of said **U**-shaped members, said pivots being co-axial with said hinges, a movable jaw slidably secured on said first mentioned frame member, means for actuating said jaw, and means carried by said 10 depending members for securing the device to a support.

3. In a device of the class described, a horizontal frame member, a pair of depending **U**-shaped members pivotally mounted in the ends thereof, a stationary jaw member carried between pivots in the return bent ends of said depending members, said pivots being co-axial with said first mentioned pivots, a plurality of vertical studs secured 20 to said horizontal frame member, a movable jaw having transverse slots adapted to bear over said studs, a cam lever pivoted on one of said studs and adapted to bear against said movable jaw, and means carried by said 25 device.

pending members for securing the device to 30 a support.

4. In a device of the class described, a horizontal frame member, a pair of depending **U**-shaped members pivoted in the ends thereof, a stationary jaw member carried 35 between pivots in the return-bent ends of said **U**-shaped members, said pivots being coaxial with said first named pivots, a plurality of vertical studs secured in said horizontal frame member, a movable jaw provided with transverse slots adapted to bear over said studs, a cam lever pivoted on one of said studs and adapted to bear against 40 said movable jaw, laterally extending portions adjacent the ends of said horizontal frame member, laterally extending portions 45 formed on said depending members, and clamp screws carried in said last named portions and adapted to clamp a supporting element against the extended portions of 50 said frame.

In testimony whereof, I affix my signature, in presence of two witnesses.

ANDREW PETERSON.
